D. L. BOGESS,
SPARK PLUG,
APPLICATION FILED APR. 19, 1916.

1,215,611.

Patented Feb. 13, 1917.

By *Watson E. Coleman*
Attorney

UNITED STATES PATENT OFFICE.

DAVID L. BOGESS, OF LIBERTY, MISSOURI.

SPARK-PLUG.

1,215,611.

Specification of Letters Patent. Patented Feb. 13, 1917.

Application filed April 19, 1916. Serial No. 92,253.

To all whom it may concern:

Be it known that I, DAVID L. BOGESS, a citizen of the United States, residing at Liberty, in the county of Clay and State of Missouri, have invented certain new and useful Improvements in Spark-Plugs, of which the following is a specification, reference being had to the accompanying drawings.

10 This invention relates to spark plugs such as are used on internal combustion engines, and the general object of the invention is the provision of a spark plug which is so constructed that the insulating core may be 15 readily removed from the bushing without the necessity of applying a wrench thereto, my invention providing for readily, quickly and easily disconnecting the insulating core and its base from the bushing in less than 20 one-third of the time required with ordinary spark plugs where a wrench has to be used.

A further object of the invention is the provision of a spark plug wherein the base 25 supporting the core is connected to the bushing by bayonet joints, and the provision in connection with the base of a latch holding the base from accidental disengagement from the bushing.

30 Other objects will appear in the course of the following description.

My invention is illustrated in the accompanying drawings, wherein:

Figure 1 is a view of a spark plug constructed in accordance with my invention, the bushing and base being in section;

Fig. 2 is an elevation of the spark plug shown in Fig. 1;

Fig. 3 is an elevation of the upper portion of the bushing;

Fig. 4 is a top plan view of the base 11; and

Fig. 5 is a top plan view of the bushing.

Referring to these figures, it will be seen 45 that, as usual, the insulating core, designated 10 and which may be made of porcelain or other suitable material of like insulating properties, is disposed within and rigidly connected to a collar or base, designated 11, which is flanged as at 12. The bushing 13 is provided with the usual many-sided head 14 whereby a wrench may be applied to it and the bushing is screw threaded, as at 15, for engagement with the wall of 55 the cylinder. Any suitable electrodes 16 are connected to this bushing. Disposed

within the core 10 is the usual electrode 17 which passes through the upper end of the core and has connected thereto the binding nut 18 whereby the electrode 17 may be connected to a source of electricity. 60

In spark plugs as ordinarily constructed, the base 11 is threaded within the bushing 13 and in order to remove the spark plug a wrench must be applied to the base and the base rotated. This is often difficult because the base has become set within the bushing, and furthermore, it takes more or less time to remove and replace the spark plug. In order to obviate these inconveniences, I form 65 the upstanding wall 19 of the bushing with a plurality of uniformly spaced bayonet slots 20, the entrance ends of these slots extending downward and at an inclination to the axis of the bushing and then extending at 70 right angles to the axis. I have illustrated three of these bayonet slots disposed equidistantly, but a greater number may be used if desired, or a less number. The base 11 is provided with a plurality of outwardly projecting pins 21 spaced equidistantly so that they may be inserted in the entrance ends of the bayonet slots and then the base rotated so as to carry these pins into the closed 75 ends of the bayonet slots in which position the base is locked from upward movement. 80

In order to hold the base in engagement with the bushing and prevent accidental rotation of the base which would tend to carry the pins 21 out of the slots 20, I preferably form the upstanding wall 19 of the bushing with a plurality of vertical slots 22, there being one of these vertical slots disposed in connection with each bayonet slot. The flange 12 of the base is also 85 notched or grooved at one point, as at 23, and mounted upon the upper face of the flange is a spring 24 having an angular end 25 which extends downward through the slot 23 and projects down below the under face of the flange or shoulder 12 so that it may engage in any one of the slots 22. In order to provide for lifting the spring 90 so as to disconnect this terminal end from the slot 21, I preferably provide the spring 100 with an upwardly projecting stud 26.

It will be obvious now that when it is desired to remove a spark plug and insert another in its place, the spring 24 may be readily raised by means of the stud 26 and 110 then the base rotated a relatively short distance and lifted from the bayonet slots.

The pins 21 will of course ride up the inclined entrance portions of the bayonet slots and thus a rotation of the base will cause the lifting of the core and base out of engagement with the bushing.

It is to be understood that the bases are to be made in standard sizes to hold any standard porcelain core, and that the bushings are also to be made in standard sizes. 10 The slots 22 are equidistantly spaced so that the pins on the base 11 will fit in any of the slots and thus eliminate the necessity of carefully adjusting the base 11. By using this bayonet joint connection no threads are 15 needed in the plug or the base. The base is to be formed with the pins 21 by casting the pins thereon and the slots are preferably formed when the bushing is cast. With small ears, the bushing and base 20 would only be formed with relatively small slots and pins and the larger the engine the larger will be the pins and the slots. The spring 24 may be riveted or otherwise connected to the base, as may be found most 25 desirable.

Having described the invention, what I claim is:

1. In a spark plug, a bushing having an

upstanding wall formed with bayonet slots and with vertical slots between the bayonet 30 slots, a core supporting base having pins engageable in said slots, and a spring detent engageable in any one of the vertical slots to prevent the reverse rotation of the base with relation to the bushing.

2. In a spark plug, a bushing having an upstanding wall formed with bayonet slots, the entrance ends of the slots being inclined to the axis of the bushing, said wall between the bayonet slots being formed with 40 vertical slots, a core supporting base having a flange, the periphery of the flange being notched at one point, and a spring attached to the face of the flange and having an angular terminal end projecting down through said notch and adapted to be engaged in any one of the vertical notches in the wall of the bushing, the spring being provided with means whereby it may be 45 lifted.

In testimony whereof I hereunto affix my signature in the presence of two witnesses.

DAVID L. BOGESS.
